UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

ADDING AND LISTING MACHINE.

968,005.

Specification of Letters Patent. Patented Aug. 23, 1910.

Application filed December 3, 1909. Serial No. 531,246.

To all whom it may concern:

Be it known that I, JESSE G. VINCENT, a citizen of the United States, residing at Detroit, in the county of Wayne and State of Michigan, have invented certain new and useful Improvements in Adding and Listing Machines, of which the following is a specification.

The primary object of the invention is 10 to equip an adding and listing machine with means whereby lists of items may be printed upon separate strips or sheets of paper independently fed or advanced step by step from a common actuating member 15 whose operative relationship with one or another paper feed means is automatically determined by the lateral shift of the paper carriage.

The invention further provides for automatically controlling a duplex accumulating mechanism so that items or amounts listed 20 on one strip or piece of paper will be added in one accumulator while items or amounts listed upon the other strip or piece of paper 25 will be added in another accumulator, the operativeness of one or the other accumulator being determined by the lateral shift of the carriage.

In the drawings which accompany and 30 form part of this specification Figure 1 represents in left side elevation an adding and listing machine equipped to accomplish results such as above mentioned; Fig. 2 is a rear elevation of such 35 machine; Fig. 3 is a top plan view of the paper carriage with portions of the sectional roller platen broken away; Fig. 4 is a section taken substantially on the line 4—4 of Fig. 2; Figs. 5 and 6 are similar fragmentary top plan views of a portion of the 40 key-board; Fig. 7 shows a portion of the machine in left side elevation with parts under a different adjustment than illustrated in Fig. 1; Fig. 8 is a partial rear 45 elevation illustrating a different adjustment than appears in Fig. 2; Fig. 9 is a perspective detail of a carriage stop-piece.

The invention is here shown as adapted 50 to the well-known Burroughs type of adding and listing machine and particularly to that development thereof which includes the duplex accumulating idea, in which connection reference may be had to Patent No. 919,656, issued April 27, 1909, on the joint 55 invention of myself and Nelson White. It

is to be understood, however, that the essential features of the present invention may be adapted to other types of adding and listing machines.

There is a carriage 17 arranged as usual to slide across the back of the machine and there is pivotally mounted upon the upper part of this carriage a rocking frame or cradle 17^a by the forward movement of which paper to be printed upon is brought into proper position for receiving imprints. In the present instance this rocking frame or cradle does not carry the usual continuous roller platen but there is journaled in it two alined roller platens A and B (Figs. 2 and 3), each secured to its own shaft or spindle and arranged to be turned step by step independently of the other. The platen shafts A' and B' journal in the end-pieces of the rocking frame or cradle in the same way that the customary single platen shaft does. At their inner ends these shafts journal in a bushing a (Fig. 3) secured in a plate 17^b carried by the cross rod 17^c of the cradle and the cradle rock shaft 17^d. The inner ends of the two roller platens 70 are preferably closed by heads a' and b' secured to them and to the shafts A' and B' respectively and center-bored to accommodate the bushing a. Each of the platen 75 shafts is turned by a ratchet-and-pawl mechanism and as one such set of devices is the same as the other a description of one will suffice. A ratchet wheel A² is secured to the shaft A' and a pair of arms C loose on 80 said shaft carry a pawl D pivoted between them and drawn by a spring e toward the ratchet wheel and normally prevented from 85 engaging the same by the contact of a cam finger d with the projecting end of the journal shaft 17^d of the rocking frame or cradle, all as shown in Fig. 1. A link E connects the pair of arms C with a plate F, the latter slotted and socketed for the engagement of a stud e carried by the link. 90 Referring next to Fig. 4 the plates F are secured to separate rock shafts A³ and B³ and these rock shafts carry bails composed of cross rods A⁴ and B⁴ and arms f connecting the same with the rock shafts. 95

It will be seen that the above-described construction provides for step-by-step advance of either roller platen quite independently of the other. However, the same actuating member serves for both platens 100 105 110

and it is of a well-known character consisting in a plate 18 arranged to slide up and down on the back of the machine and having jaws 18^a adapted to embrace either of the bail cross rods A⁴ or B⁴ according to the lateral position of the carriage. It is obvious that these bails being normally in alinement one may pass out from between the jaws and the other in between the jaws when the carriage is shifted. The plate 18 is reciprocated in the usual way by a lever 18^b coupled at the rear end to the plate, and a cam 18^c secured to the rock shaft 100 and having a slot embracing a roller 18^d on the forward end of the lever 18^b,—all as shown in Fig. 1.

It will be understood of course that separate strips or sheets of paper will pass around the two roller platens. In the present instance holders A⁵ and B⁵ (Figs. 1 and 2) are shown designed to carry two separate rolls of paper and having well-known or any suitable equipment for keeping the strip or web of paper in the proper line the holders being laterally adjustable on their supporting cross-rods. These separate webs of paper will be entered between their respective platens and suitable pressure rollers A⁷, B⁷ and one web or the other will be advanced according to the position of the carriage, said pressure rollers being independently rotatable. It will be seen that the arrangement described provides for printing upon one web of paper and advancing the same without the other web of paper being affected at all. Then the carriage can be shifted and the web of paper previously printed upon is not affected when the other is printed upon and advanced. Two separate lists of items can thus be run off on separate pieces of paper in the same machine and by the operation of the same actuating member and without feed movement of the piece or web of paper not in use.

It is of course desirable that each roller platen have the usual facilities in the matter of turning by hand in one direction or the other and therefore each of the shafts A' and B' carries at the outer end a knob or twirler A⁶, B⁶. Then there is provided for each platen the usual dolly roll g spring-held in engagement with the associated ratchet wheel, as illustrated in Figs. 1 and 2, for the purpose of preserving the proper spacing when the platen is rotated.

To fix the carriage in the proper lateral position or positions there is secured to the back of the machine a notched plate H and on a rock shaft G in the lower part of the carriage there are adjustably secured fingers H' adapted to engage the notched plate, being constrained to do so by spring h applied to lever h' loose on shaft B³ and cranked to said rock shaft (Fig. 2). The same pieces of which said fingers constitute

parts are utilized for the purpose of controlling the duplex accumulating mechanism such as disclosed in the before-mentioned Patent No. 919,656, as will now be described.

Each finger H' has formed upon its hub 70 a flange h², as shown in Fig. 9, and the flanges of the two fingers herein shown are adapted to act against vertical shoulders of a plate I on the rear of the machine (see Fig. 2). This plate is slotted longitudinally 75 to embrace guiding studs i on the casing or framework of the machine and is adapted to be slid one way or the other by action of the flanges h² against the said vertical shoulders. The latter are designated respectively i' and 80 i² and are at opposite ends of a raised portion of the plate. This raised portion is not of great extent and may of course vary in extent but as here shown it provides for the shifting of the carriage a comparatively 85 limited amount to change from one web of paper to the other. Of course this raised portion measures the minimum extent of such shifting of the carriage and the fingers H' can of course be spaced apart varying 90 distances to provide for a greater extent of shift of the carriage. Under the adjustment illustrated in Fig. 3 it will be seen that the carriage moves a considerable distance before the shoulder i² is encountered by the 95 flange of the stop finger. This arrangement provides for varying conditions as to width of paper without requiring any adjustment other than the setting of the stop fingers.

The sliding plate I has a depending portion formed with an oblique slot i³ which receives a roller j on an arm J, the latter secured to a rock shaft j' in a bearing on the back of the machine and carrying at the inner end another arm J', (Figs. 1 and 100 7; see also dotted lines, Fig. 8). This arm J' is pivoted to a link j² and the latter is pivoted to an arm j³ secured to a rock shaft 105 501 carrying another arm j⁴. Loose upon the shaft 501 is an upstanding arm K to 110 which is pivoted a link k which at its forward end is pivoted to the lower end of a lever 10 corresponding with the lever so designated in said Patent No. 919,656. The aforesaid arm K has a roller stud k' which 115 co-acts with a V-shaped cam L on a curved arm L' pivoted to the arm j⁴ and connected by a spring j⁵ with an ear on the hub of the latter, as shown in Figs. 1 and 7.

With the carriage in the right-hand position, as illustrated in Fig. 2, the arm J is elevated by reason of the roller j being in the upper end of the oblique cam slot i³ and in consequence the inner arm J' is down as in Fig. 1 and the arm j⁴ up with the V-shaped 125 cam L to the rear of the roller stud k', as shown in Fig. 1, the arm K being thus held forward. When the carriage is shifted to the left the plate I is likewise shifted and the arm J is rocked to the position shown in 130

* Fig. 8 and the arm J' correspondingly elevated so that the V-shaped cam L is carried to the front side of the roller k' and the spring causes said cam to shift the arm K rearward as illustrated in Fig. 7. This shifting of the arm K throws the lever 10 back and forth the same as it is moved by hand in the construction described in said patent and with like result in alternately rendering active the department of the duplex accumulating mechanism.

The accumulating mechanism is practically the same as illustrated in said patent and a full description of it need not be given since such will be found in said patent to which reference has been made. Suffice it to state that the pinions of the upper accumulator are designated 618 and those of the lower accumulator 618^a and that with the carriage in the right-hand position the upper accumulator is active, whereas with the carriage in the left-hand position the lower accumulator is the active one.

It will be obvious that the arrangement described insures that items listed upon the web of paper at the left of the carriage will be accumulated in the upper accumulator and that items listed upon the other web of paper will be accumulated in the lower accumulator.

Instead of having the lever 10 project above the keyboard as in said patent it is here shown as cut off below the upper keyboard plate and connected to a slide plate 35 inscribed with the letters "U" and "L", indicating upper and lower accumulators, such letters being adapted to be alternately displayed through an opening in the keyboard, as illustrated in Figs. 5 and 6. This 40 or any other distinguishing arrangement can be employed to denote to the user at a glance which one of the accumulators is ready to receive items. Instead of the letters or in addition thereto contrasting colors may 45 be used.

While the above-described construction is well adapted to fulfil the object primarily stated, it is to be understood that such construction can be modified considerably within 50 the scope of the invention.

What is claimed is:

1. In a machine of the character described, the combination of a laterally shiftable carriage having a sectional paper support, means applied to each section for advancing paper independently of the other section, and means common to the several paper-advancing means for operating the latter.

2. In a machine of the character described,

the combination of a laterally shiftable carriage having a sectional roller platen and pressure rollers, means applied to each section of said platen for turning it step by step independently of the other section, and means common to said platen-turning means for operating the same.

3. In a machine of the character described, the combination of a laterally shiftable carriage having a sectional roller platen and pressure rollers, ratchet wheels on the platen sections respectively, pawls and pawl carriers and operating connections for the respective ratchet wheels, and means common to said connections for actuating the same.

4. In a machine of the character described, the combination of a laterally shiftable carriage having a sectional roller platen and pressure rollers, ratchet wheels on the platen sections respectively, pawls and pawl carriers, bails and connections between the same and the pawl carriers respectively, and an actuating member common to the bails having sliding engagement therewith.

5. In a machine of the character described, the combination of a laterally shiftable carriage having a sectional paper support, means applied to each section for advancing paper independently of the other section, means common to the several paper-advancing means for operating the latter, duplex accumulating mechanism, and controlling devices therefor regulated by the shifting carriage.

6. In a machine of the character described, the combination of a laterally shiftable carriage having a sectional paper support, means applied to each section for advancing paper independently of the other section, means common to the several paper-advancing means for operating the latter, printing mechanism common to the sections of the paper support, accumulators for separately accumulating items listed on the paper of different supports, and means for alternately actuating the accumulators as regulated by the position of the shifting carriage.

7. In a machine of the character described, the combination of a laterally shifting carriage, duplex accumulating mechanism, and controlling devices therefor regulated by the shifting carriage and including a slide shouldered for engagement by carriage parts and cam-slotted, and an arm engaging the cam-slot.

JESSE G. VINCENT.
